HEAT RADIATOR

Forrest S. White, Hoosick Falls, and Claude G.
Bordeaux, Albany, N. Y.

Application May 8, 1934, Serial No. 724,500

12 Claims. (Cl. 257—150)

Our invention more particularly relates to a heat radiator for use in an automobile or other vehicle, although our invention is not limited to this particular use.

5 One of the objects of our invention is the provision of a heat radiator which is simple in construction and which is compact and efficient in operation.

10 A specific object of our invention is the provision of a radiator comprising two groups of radiating fins in good thermal relation with the steam pipe, the fins of one group being staggered with respect to the other group whereby heat is effectively transferred from the radiating fins to 15 the air which passes thereover.

Other novel features of our invention will appear in the specification and will be particularly pointed out in the claims.

Our invention will best be understood by reference to the accompanying drawing in which we have illustrated a preferred embodiment thereof and in which—

20 Fig. 1 is a side view, partially in section, of a radiator embodying our invention and the parts associated therewith;

Fig. 2 is a rear elevation of the radiator;

Fig. 3 is a section taken along the line 3—3 of Fig. 2; and

25 Fig. 4 is a section taken along the line 4—4 of Fig. 2.

Like reference characters indicate like parts throughout the drawing.

The radiator embodying our invention is indicated generally at 10 and comprises a fluid heating pipe 11 which is preferably vertically arranged as indicated in Fig. 2, the fluid heating supply pipe 12 being connected to the upper end of said radiator and a return pipe 13 to the lower end. Hollow metallic cross members 14 are preferably provided which are closed at their outer ends as at 15 as best indicated in Fig. 4 and which communicate with the said pipe 11, the cross members 14 preferably being inclined downwardly and inwardly from their ends to the said pipe 11 45 to permit condensate to drain therefrom.

Two groups of annular radiating fins arranged one within the other and indicated generally at 16 and 17, respectively, are spaced from each other as at 18, individual fins 19 of one group 50 being staggered with respect to those of the other group, the fins of each group being connected to the heating pipe 11 and the cross members 14 at spaced points thereof. Referring particularly to Fig. 3 the fins 191 of one group are staggered with 55 respect to the fins 192 of the other group thereby

causing the air flowing from the fins of one group to the fins of the other group to be impeded and subjected to a turbulent action which mixes the air and brings the various portions thereof into engagement with the fins more effectively than would be the case if the fins were continuous. In the latter case the portions of the air within the air stream would not find its way to the fins, at least not as effectively as it is in accordance with our invention. Furthermore, by offsetting 10 the fins of one group from those of the other group, the air is caused to impinge against the fins more effectively than would be the case with straight passages.

It will be noted that portions of the radiating fins extend away from the steam pipe, thereby creating openings between the fins through which air may flow.

The outer fin of the group 17 is preferably provided with a peripherally extending rib 20 forming with the fin a shoulder 21 for a purpose which will hereinafter appear. The front end of the radiator is preferably provided with a forwardly extending lug 22 provided with a tapped opening 23 in which a bolt for the support of an air deflector (not illustrated) is received.

The pipe 11 and the cross metallic members 14 are formed about a sand mold while the fins and the remaining portion of the radiator are preferably formed by a permanent metallic mold 30 two portions of which are brought together while a suitable metal such as aluminum or a composition thereof is poured into the mold. The fins are thus integral with the steam pipe and with the cross metallic members thus being in intimate 35 thermal conducting relation therewith. It will be understood that the spaces between the two groups 16 and 17 of radiating fins may be formed by plates in the mold which are removed when the radiator is taken therefrom. When the casting 40 has been formed, the permanent molds are separated and the radiator removed therefrom, and the sand removed from the pipe 11 and the cross arms through openings formed in the ends of the said pipe. The fins 19 are preferably 45 tapered as best shown in Figs. 3 and 4, the thinner portions of the ribs being at their outer extremities to permit the ready removal of the casting from the permanent molds.

It will be understood that the closed ends of 50 the cross metallic members 14 are integral with the outer fin thereby forming a support therefor.

In accordance with our invention both the steam pipe 11 and the cross metallic members 14 are elongated on their exterior portions in 55

the direction of the fins thereby extending the metallic portions of said pipe and the cross arms close to the edges of the fins and increasing the heat conductivity from the said pipe and the cross arms to the fins. We have found, for example, that when the fins of the group 16 are approximately one inch wide and those of the group 17 approximately one inch and a quarter wide that the pipe 11 and the cross arms may advantageously extend to points about three-eighths of an inch from the edges of the fins, although it will of course be understood that our invention is in no wise limited to the dimensions designated. The walls of both the pipe 11 and the cross metallic members are preferably of substantially uniform thickness, although it will be understood that the exterior portions of said pipe and of the cross metallic members could be elongated by thickening the walls thereof at the front and rear of the radiator as viewed in Figs. 2 and 3.

A supporting housing 24 may conveniently be received against the rib 20 on the outer fin of the group 17 and rest on the shoulder 21, the housing surrounding the group 16 in the manner best shown in Fig. 1. The inner end of the housing 24 is preferably provided with inwardly extending brackets 25 to which is secured the housing 26 of an electric motor which actuates the fan 27 which forces air over the radiator, it being understood that air passes through an opening 28 formed in the housing 24.

While we have described our invention in its preferred embodiment, it is to be understood that the words which we have used are words of description rather than of limitation. Hence, changes within the purview of the appended claims may be made without departing from the true scope and spirit of our invention in its broader aspects.

40. What we claim is:

1. In a radiator, a heating pipe, hollow metallic cross members closed at their ends communicating with said pipe, and a plurality of spaced radiating fins integral with said pipe and with said cross members.

2. In a radiator, a heating pipe, hollow metallic cross members closed at their ends communicating with said pipe and inclined downwardly and inwardly from their ends towards said pipe, and a plurality of spaced radiating fins integral with said pipe and with said cross members.

3. In a radiator, a heating pipe, hollow metallic cross members closed at their ends communicating with said pipe and inclined downwardly and inwardly from their ends towards said pipe, and a plurality of spaced radiating fins integral with said pipe and with said cross members, said pipes and said cross members being elongated in cross section on their exterior in a direction of the planes of said fins.

4. In a heat radiator, a heating pipe, two spaced groups of radiating fins in good thermal conducting relation with said pipe, the fins of one group being staggered with respect to those of the other group, the fins of a given group extending in the same general direction as those of the other group, and means for directing the gas to be heated successively over said groups.

5. In a heat radiator, a heating pipe, two hollow metallic cross members closed at their ends and communicating with said pipe, said cross mem-

bers being inclined downwardly and inwardly from their ends towards said pipe, two spaced groups of radiating fins each group comprising a plurality of spaced fins in good thermal conducting relation with said pipe, the fins of one group being staggered with respect to those of the other group and said pipe being elongated in cross section on its exterior in a direction of the planes of said fins. 5

6. In a heat radiator, a heating pipe, two hollow metallic cross members closed at their ends and communicating with said pipe, said cross members being inclined downwardly and inwardly from their ends towards said pipe, two spaced groups of radiating fins each group comprising 15 a plurality of spaced fins integral with said pipe, the fins of one group being staggered with respect to those of the other group and said pipe being elongated in cross section on its exterior in a direction of the planes of said fins. 20

7. In a heat radiator, a vertically disposed heating pipe, a steam inlet communicating with the upper end of said pipe and a return pipe communicating with the lower end thereof, two hollow metallic cross members closed at their ends 25 and communicating with said pipe, said cross members being inclined downwardly and inwardly from their ends towards said pipe, two spaced groups of radiating fins each group comprising a plurality of spaced fins in good thermal 30 conducting relation with said pipe, the fins of one group being staggered with respect to those of the other group and said vapor pipe being elongated in cross section on its exterior in a direction of the planes of said fins. 35

8. In a radiator, a heating pipe, hollow metallic cross members closed at their ends and communicating with said pipe, and a plurality of annular spaced radiating fins in intimate thermal conducting relation with said pipe and with said 40 cross members, said pipe being elongated in cross section on its exterior in a direction of planes of said fins.

9. In a radiator, a heating pipe, hollow metallic cross members closed at their ends and communicating with said pipe, and a plurality of annular spaced radiating fins in intimate thermal conducting relation with said pipe and with said 45 cross members.

10. In a radiator, a heating pipe, hollow metallic cross members closed at their ends and communicating with said pipe, and a plurality of annular spaced radiating fins in intimate thermal conducting relation with said pipe and with said 50 cross members.

11. In a heat radiator, a heating pipe, a plurality of annular radiating fins in good thermal relation to said pipe and arranged one within the other in the same general plane, said fins having portions extending away from said pipe 60 whereby air may flow between said fins. 55

12. In a heat radiator, a heating pipe, a plurality of annular radiating fins in good thermal relation to said pipe and arranged one within the other in the same general plane, said fins 65 having portions extending away from said pipe, whereby air may flow between said fins, said pipe being elongated on its exterior in a direction of the planes of said fins.
